UNITED STATES PATENT OFFICE.

FREDERICK SAMUELSON, OF RUGBY, ENGLAND, ASSIGNOR TO GENERAL ELECTRIC COMPANY, A CORPORATION OF NEW YORK.

VAPOR GENERATOR.

Application filed June 1, 1925, Serial No. 33,892, and in Great Britain July 4, 1924.

This invention relates to vapor generators and more particularly to generators of the type in which a liquid such as mercury is evaporated within rotating tubes, a layer of mercury being continuously kept in contact with the inner surface of each rotating tube.

The object of the invention is to provide means whereby the quantity of mercury required within the tube may be reduced without decreasing the heating surface. A further object is to provide means for damping the surging of the mercury, in the tube, in cases where the generator is mounted on a moving platform, for example, on board ship or in an air vessel.

This invention comprises providing a device within the rotating tube which while occupying a considerable space in close proximity to the inner surface of the tube, does not prevent the mercury or other liquid being evaporated, from coming into actual contact with the heated inner wall of the tube, passages being provided to permit of the mercury being fed into contact with the tube along its entire length, and also to permit of the vapor generated being drawn off and utilized.

The accompanying drawings illustrate one method of carrying my invention into effect, Fig. 1 being a longitudinal section through a tube fitted with my improvements; Fig. 2 a cross section on the line 2—2, Fig. 1; Fig. 3 a cross section on the line 3—3, Fig. 1; and Fig. 4 is a fragmentary sectional view of the tube on a larger scale.

In the drawing, 1 represents a rotating tube or casing in which mercury or other liquid is to be evaporated. This tube is provided with suitable end covers 2, fitted with ball or roller bearings 3, suitably supported from the housing of the boiler, so that the tube is free to rotate. Secured to the covers 2 are pipes 4 and 5 through the former of which mercury is fed into the rotating tube, while the vapor generated passes out through the latter tube.

Inside the main tube 1, I fit a cage 6, comprising a tubular member having boxes or chambers 7 formed therein. As will be seen from Fig. 2, these boxes or chambers have a considerable circumferential length in proximity to the inner walls of the tube 1, but this length is considerably reduced at the point 8. With such a construction, it is possible to

have a considerable pressure exerted due to the centrifugal force of the mercury in the boxes or chambers 7 without an excessive weight of mercury being contained in the tube. This is owing to the fact that the pressure due to centrifugal force in the constricted portion 8 is transmitted through the body of mercury contained in the box or chamber 7, and acts as if the rotating tube contained a layer of mercury everywhere equal to the thickness of the rotating cage 6. The cage is so arranged that the fluid to be evaporated can be fed in through the pipe 4 to any desired points of the tube simultaneously. This is attained by fitting a pipe 9 along the central axis of the cage, and supported within the end wall of the cage, and also in the center wall or spider 9^a at the middle of the cage. This pipe 9 feeds fluid up suitable radial passages 9^b to the annular ring or chamber 10, and thence by means of passages 11 into the boxes of the rotating cage. This is clearly shown in Fig. 3. Apertures 12 are provided in center wall 9^a to allow of the passage of the vapor generated from one side of the central wall or spider to the other. Ducts 13 are provided, as clearly shown in Figs. 1 and 2, to permit of the slow passage of mercury from one box or chamber 7 to another, and thus prevent surging should the generator be mounted on a moving platform.

The vapor generated passes through the pipe 5 to the means provided to convert the energy contained in it into useful work, for example, in a turbine or other prime mover.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. In a boiler of the rotating tube type, the combination of a rotatable casing, and a filler structure in the casing which defines with the casing inner and outer chambers connected by radially extending passages of narrow width.

2. In a boiler of the rotating tube type, the combination of a casing, and an annular cage therein, said cage being provided

with recesses which form with the inner surface of the casing chambers having comparatively large circumferential length, and said cage being provided with passages which serve to connect the chambers to the interior of the cage.

3. In a boiler of the rotating tube type, the combination of a casing and an annular cage therein, said cage being provided with recesses which form with the inner surface of the casing chambers having comparatively large circumferential length, and said cage being provided with passages which serve to connect the chambers to the interior of the cage, and means for feeding liquid into the casing at a plurality of points.

4. In a boiler of the rotating tube type, the combination of a casing and an annular cage therein, said cage being provided with recesses which form with the inner surface of the casing chambers having comparatively large circumferential length, and said cage being provided with passages which serve to connect the chambers to the interior of the cage, the walls of said chambers being provided with passages which serve to connect together adjacent chambers and permit of the slow passage of liquid from one chamber to another.

5. In a boiler of the rotating tube type,

the combination of a casing, and a structure in the casing which defines with the inner surface of the casing a plurality of circumferentially-extending liquid chambers and radially-extending passages which connect such chambers with the central portion of the casing.

6. In boiler of the rotating tube type, the combination of a casing and an annular structure therein comprising longitudinally-extending members which provide with the inner surface of the casing chambers which are open to the inner surface of the casing over the major portion of its area, and passages connecting said chamber to the interior of the structure.

7. In a boiler of the rotating tube type, the combination of a casing and an annular structure therein comprising longitudinally-extending members which provide with the inner surface of the casing chambers which are open to the inner surface of the casing over the major portion of its area and passages connecting said chambers to the interior of the structure, and means for feeding liquid into said chambers at a plurality of points.

In witness whereof, I have hereunto set my hand this fifteenth day of May 1925.

FREDERICK SAMUELSON.
